UNITED STATES PATENT OFFICE.

JAMES C. COVERT, OF WATERVLIET, NEW YORK.

DESIGN FOR A KEEPER-SPRING.

SPECIFICATION forming part of Design No. 26,541, dated January 19, 1897.

Application filed December 17, 1896. Serial No. 616,075. Term of patent 14 years.

To all whom it may concern:

Be it known that I, JAMES C. COVERT, a citizen of the United States, residing at Watervliet, (formerly West Troy,) in the county of Albany and State of New York, have invented and produced a new and original Design for a Keeper-Spring; and I do hereby declare the following to be a full, clear, and exact description of the same, reference being had to the accompanying drawings, forming a part thereof.

This invention relates to an original design for a keeper-spring for attaching devices, and it is embodied in the structure hereinafter described, and shown in the accompanying drawings, forming part of this specification.

In the drawings, Figure 1 is a side elevation of a keeper-spring embodying the design, and Fig. 2 is a perspective view of the same.

A designates the main or tongue portion, which is straight and flat, its free end being slightly rounded.

B designates the curved rear part, the end

C of which is curved and carried forward for a short distance substantially parallel with the part or section A. The forward end of the part or section C is curved downward and backward, forming a well-defined hook-section D, which is located below the plane of the section C.

The essential feature of the design is the keeper, as shown, with the well-defined hook-section D.

Having thus described my new and original design, what I claim, and desire to secure by Letters Patent, is—

The keeper-spring, substantially as shown and described.

In testimony whereof I affix my signature in presence of two witnesses.

JAMES C. COVERT.
